J. McL. MURPHY,
CENTRIFUGAL SEPARATOR,
APPLICATION FILED AUG. 14, 1912.

1,146,438.

Patented July 13, 1915

UNITED STATES PATENT OFFICE.

JOHN MCLEOD MURPHY, OF HABANA, CUBA, ASSIGNEE TO WALTER WOOD, OF PHILADELPHIA, PENNSYLVANIA.

CENTRIFUGAL SEPARATOR.

1,146,438.

Specification of Letters Patent. Patented July 13, 1915.

Application filed August 14, 1912. Serial No. 715,082.

To all whom it may concern:

Be it known that I, JOHN MCLEOD MURPHY, a citizen of the United States, residing at Habana, Cuba, have invented certain new and useful Improvements in Centrifugal Separators, of which the following is a specification.

My invention relates to centrifugal separators of the vertical type.

10 The object of the invention is to provide the rotary foraminated bowl with centrally disposed means for continuously feeding the material into its bottom portion and similarly located means for continuously carrying away the dried material, or material from which a constituent portion has been extracted or separated by centrifugal action.

This object I accomplish by the construction shown in the accompanying drawing in which the figure represents a central vertical section of a centrifugal separator containing my improvements.

5 indicates a stationary imperforate bowl-shaped casing suitably supported on the support 6 and provided with a discharge outlet 7 in its lower portion. Mounted in the bearing 8, in the bottom of the stationary casing 5, is a vertical shaft 9, provided at its upper end with a pulley 10, to which power is transmitted by means of the belt 11. Supported rigidly on the shaft 9, within the casing 5, is the perforated separating bowl 12, adapted to be rotated by the said shaft 9. Loosely surrounding the shaft 9 and extending substantially to the bottom of the bowl 12 is a rotary sleeve 13, driven by pulley 16 and belt 17 and provided on its exterior with the spiral flange 14, which forms a screw conveyer adapted to convey the material to be separated to the bottom of the bowl 12. The screw conveyer 14 works within the stationary inlet or feed tube 15.

The inlet or feed tube 15 at its upper end is preferably formed into a funnel shaped receiver 18, to which the material to be separated is fed, as by a spout 18' extending from a supply tank 18''. From the construction thus far described it will be seen that the material fed into the funnel 18 will, when the screw conveyer 14 is rotated in

the proper direction, be fed down into the bottom of the perforated separating bowl 12 since the inlet tube 15 does not extend down into contact with the bowl but is spaced therefrom.

Surrounding the inlet tube 15 is a stationary supporting tube 19 secured at its upper end to the bracket 21 and carrying at its lower end a stationary outlet bowl 20, the sides of which are perforated. The stationary bowl 20 is mounted concentrically to the rotary bowl and is of less height than bowl 12 so that the dried material as it rises in rotary bowl 12 will overflow into the stationary bowl 20. This action is assisted by the upper portion of the separating bowl 12 inclining inwardly above the upper edge of the outlet bowl 20.

Loosely surrounding the supporting tube 19 is a rotary tube 22, provided on its exterior with a spiral 23 forming a screw conveyer, with a screw pitched in opposite direction from that of the spiral 14. The tube 22 carrying the screw conveyer 23 is driven by means of a pulley 24 on its upper end, operated by a belt 25. Surrounding the screw conveyer 23 is a stationary outlet tube 26 having at its upper end the enlarged chamber 27 which communicates with a discharge pipe 28. It will be noted that the outlet tube 26 does not extend down to the bottom of the bowl 20, but its lower end is spaced from the bowl, and therefore this last mentioned conveyer will operate to withdraw material from the bottom of the bowl 20, and discharge it through the chamber 27 into the discharge pipe 28.

From the foregoing description it will be seen that when power is applied to the pulleys 10, 16, and 24, to drive them in the proper direction, and at the proper speed, the material to be separated, such as sugar, may be admitted into the receiver 18 from the tank 18''; and the screw conveyer 14 will then operate to carry the material down to the bottom of the separating bowl 12. Here it will work up the sides of the bowl from the center, due to the centrifugal force exerted by the bowl, and the liquid carried by the sugar will be thrown out into the cas-

ing 9, from which it is drawn off by the discharge pipe 7. As the material to be separated is continuously fed into the separating bowl 12 the dried material remaining in the bowl, such as the sugar will rise above the edge of inner bowl 20 and will begin to drop inwardly over the edge thereof. The separated material will continue to flow inwardly over the top edge of the bowl 20 until finally it gets in the path of the screw conveyer 23, and by this conveyer it will be drawn up through the outlet tube 26 and discharged through the discharge pipe 28. By varying the speed of rotation of the feed and delivery screws with reference to the speed of rotation of the bowl 12 the separating action can be varied to suit different conditions, as may be desired.

It is evident that my invention is applicable not only to the separation of sugar but to separating moisture from any other material of a similar nature that may be found desirable.

I realize that considerable variation is possible in the details of construction and arrangement of parts without departing from the spirit of my invention, and I therefore do not intend to limit myself to the specific form shown and described.

Having thus described my invention what I claim as new and desire to secure by Letters Patent is:

1. A centrifugal separator comprising a vertically disposed perforated separating bowl, means for rotating the bowl, a supply or feeding means leading centrally through the upper end of the bowl the bottom of said bowl, and means for conveying the treated material centrally from the said bowl at a point above its supply or feed point.

2. A centrifugal separator comprising a vertically disposed, perforated, separating bowl, means for rotating the bowl, a central vertical screw conveyer for feeding the material to be treated into the bowl at a point adjacent the bottom, a central outlet screw-conveyer for receiving the treated material above the point above where the material is fed into the bowl.

3. A centrifugal separator comprising a rotary, vertically disposed separating bowl, an inner concentric outlet bowl of less height than the separating bowl to receive the treated material, means for feeding the material to be treated into the separating bowl at a point adjacent the bottom, and means for conveying the treated material from the inner outlet bowl.

4. A centrifugal separator comprising a rotary, vertically disposed separating bowl curved inwardly toward its upper end, an inner concentric outlet bowl of less height

than the separating bowl to receive the treated material, means for feeding the material to be treated, into the separating bowl, at a point adjacent the bottom, and means for conveying the treated material from the inner outlet bowl.

5. A centrifugal separator comprising a rotary, vertically-disposed separating bowl, a central downwardly feeding screw conveyer leading to the bottom of the bowl to supply the material to be treated, an inner concentric outlet bowl of less height than the separating bowl and through which the feed conveyer extends, and an upwardly discharging screw conveyer extending upwardly from the bottom of the outlet bowl, and concentric with the feed conveyer.

6. A centrifugal separator comprising a vertical, stationary outer bowl, an inner rotary separating bowl, and a stationary outlet bowl within and of less height than the separating bowl, a vertical screw conveyer extending down centrally to a point near the bottom of the separating bowl to supply the same with material to be treated, an outlet screw conveyer concentric with the first conveyer and leading upwardly from the outlet bowl, a discharge leading laterally from the upper end of the outlet conveyer, and means for feeding the material into the upper end of the feeding conveyer.

7. In a centrifugal separator, the combination with a bowl, of means for driving the same, means for feeding material to be separated to the bottom of the same, a second bowl, concentric with the first bowl, means for supporting said second bowl, and means for delivering separated material from the bottom of said second bowl.

8. In a centrifugal separator, the combination with a bowl, of means for driving the same, means for feeding material to be separated to the bottom of the bowl, a second bowl concentrically mounted within the first bowl, means for supporting said second bowl, and means for delivering separated material from the bottom of said second bowl.

9. In a centrifugal separator, the combination with a bowl, of means for driving the same, a screw conveyer for feeding material to be separated to the bottom of the same, a second bowl concentric with the first bowl, means for supporting said second bowl, and a second screw conveyer for delivering separated material from the bottom of said second bowl.

10. In a centrifugal separator, the combination with a shaft, a bowl mounted on the shaft, of means for driving the shaft to rotate the bowl, a screw conveyer surrounding the shaft and adapted to continuously feed the material to be separated into the bowl,

a tube surrounding the screw conveyer, a second bowl mounted on the tube within the first mentioned bowl, a screw conveyer surrounding the tube and means for driving 5 the last mentioned screw conveyer continuously to deliver material from the second mentioned bowl.

In testimony whereof I affix my signature in presence of two witnesses.

JOHN McLEOD MURPHY.
